UNITED STATES PATENT OFFICE.

SAMUEL J. NEWMAN, OF NEW HAVEN, CONNECTICUT, ASSIGNOR TO I. NEWMAN & SONS, OF NEW HAVEN, CONNECTICUT, A PARTNERSHIP.

CORSET.

1,356,392.

Specification of Letters Patent. Patented Oct. 19, 1920.

Application filed September 26, 1919. Serial No. 326,440.

To all whom it may concern:

Be it known that I, SAMUEL J. NEWMAN, a citizen of the United States, and a resident of New Haven, in the county of New Haven 5 and State of Connecticut, have invented a new and useful Corset, of which the following is a full, clear, and exact description.

This invention relates to an improved construction of a front-lace corset and is an 10 improvement over the construction shown in my former Patent No. 1,256,354, issued February 12, 1918. The object in view is to provide an improved construction which will have the advantages of my former patent and at the same time present a comparatively cool light device.

Another object, more specifically, is to provide a front-lace corset of a type similar 20 to that shown in my former patent while arranging the elastics so that there will be appreciable openings there-between, same being associated with steel or whale-bone 25 pockets extending across the openings whereby the flesh cannot protrude through where ventilation will be provided.

In the accompanying drawing:

Figure 1 is a figure of a person with a 30 corset embodying the invention shown in the first stage of application.

Fig. 2 is a figure similar to Fig. 1, but showing the corset in the second stage of application.

Fig. 3 is a view similar to Fig. 2, but showing the corset completely applied.

Fig. 4 is a transverse horizontal section 35 through the corset shown in Fig. 3, the same being on an enlarged scale.

Fig. 5 is a fragmentary rear view of the upper part of the corset shown in Fig. 1 40 illustrating spaced elastic members.

Referring to the accompanying drawing by numerals, 1 indicates the body of a front lace corset of the type shown in my former Patent No. 1,256,354. However, instead of 45 forming the back completely solid as shown in my former patent the back is preferably provided with a plurality of spaced elastics 2, while at the front the vest structure 3 is provided, which is connected together

50 in any desired manner, and over which the flaps or extensions 4 and 5 of body 1 extend as shown particularly in Figs. 2 and 3 when the corset is in proper position for use. The vest 3 is similar to the construction shown in 55 my prior patent, but is formed with a plu-

rality of spaced elastic webs 6 instead of having them in contact whereby ventilating openings 7 are produced. One edge of the elastic 6 is connected to the body 1 and on the opposite edge is provided with fastening means 8 and 9 which are shown as interlocking clasps, but any other form of fastening means could be used without departing from the spirit of the invention. The openings 7 are made as large as possible in order 60 to secure ample ventilation, but to prevent the flesh from protruding steel or whale-bone pockets 10 are provided for each set of elastics 6 whereby the openings 7 are provided and consequently the flesh is properly 65 held in place though the ventilation is not interfered with. These elastics provide ventilation at the front of the corset while the spaced elastics 2 provide for ventilation at the rear. The pockets 10 are preferably 70 formed of the same grade of cloth as body 1 and are stitched in place in any desired manner so as to receive any usual form of 75 steel or whale-bone.

In operation the corset is first passed 80 around the body and the posts and eyes 11 and 12 are interlocked as shown in Fig. 1, after which the lacing is begun as shown in Fig. 2. This lacing is drawn tight preferably as it is applied so that when the lacing is finished the corset is properly fitted to the person as shown in Fig. 3. When the corset is in the position shown in Fig. 1 the elastics are preferably slightly stretched 85 so as to hold the corset in proper position, so that when the flaps 4 and 5 are folded over as shown in Fig. 2 they will be spaced 90 apart. As the lacing is applied these flaps will be brought together and consequently 95 the strain will be taken off the elastics so that there will be no resilient pressure against the body, but merely the usual support of the corset body. This construction and arrangement presents a very cool construction of 100 corset for use in the summer, or if desired for use at any time, while retaining all the advantages of my former patent above mentioned.

What I claim is:—

1. A corset of the character described comprising a body open at the front, said body being formed with spaced elastics at the rear opposite the spine whereby ventilation for the back is produced, a vest structure arranged at the front connected to the body 110

at a distance from the edges of the body, said vest structure comprising a plurality of spaced elastics for producing ventilation, and connecting means arranged centrally 5 of the body when interlocked, and means for drawing the edges of the body toward each other over the vest structure.

2. A corset of the character described comprising a body open at the front, means for

drawing the edges of the body toward each 10 other, a vest structure formed with spaced elastic strips with a steel receiving pocket extending across the elastics on each side of the center of the body and across the openings therebetween for preventing the protrusion of the flesh without interfering with the circulation of air.

SAMUEL J. NEWMAN.
